Int. Cl. D26—02

U.S. Cl. D48—23

FIG. 1 is a perspective view of a fluorescent lighting fixture showing my new design, the lights being broken away to indicate indeterminate length.

FIG. 2 is a plan view thereof.

FIG. 3 is a plan view of a second embodiment of the fluorescent lighting fixture.

FIG. 4 is a plan view of a third embodiment of the fluorescent lighting fixture.

The lights are fragmentarily shown in FIGS. 2, 3 and 4 for convenience of illustration.

The support member is shown in broken lines in FIGS. 1 through 4 for illustrative purposes only.

This is a division of design application Ser. No. D-10846 filed Mar. 4, 1968, now Design Pat. No. D-218,356.

I claim:

The ornamental design for a fluorescent lighting fixture, as shown and described.
